UNITED STATES PATENT OFFICE

2,007,901

MINING APPARATUS

Charles F. Osgood, Claremont, N. H., assignor to
 Sullivan Machinery Company, a corporation of
 Massachusetts

Application October 17, 1930, Serial No. 489,383
 Renewed June 16, 1933

105 Claims. (Cl. 262—28)

This invention relates to mining apparatus and more particularly has reference to improvements in the adjustable supporting structure for the cutting appliances of an apparatus for mining coal.

5 An object of this invention is to provide an improved coal mining apparatus. Another object is to provide an improved adjustable supporting structure for the cutting appliances of such an apparatus. A further object is to provide an 10 improved adjustable supporting structure for the cutting appliances of such an apparatus whereby kerfs may be cut in the coal in any desired horizontal plane between the mine roof and mine floor. Another object is to provide an improved 15 coal mining apparatus of the so-called combined horizontal and shear cutter type. Yet another object is to provide an improved revoluble supporting structure for the cutting appliances of a coal mining apparatus whereby kerfs may be cut 20 in the coal in either horizontal or vertical planes and including an adjustable supporting structure whereby the cutting appliances may be positioned to cut in parallel planes in any operating position of the cutting appliances. A further object 25 is to provide in an apparatus of the character set forth an improved adjustable supporting structure for the cutting appliances whereby the latter may be adjusted into parallel horizontal planes and parallel vertical planes while the same are 30 maintained at all times parallel to the longitudinal axis of the apparatus and having associated therewith improved means for tilting the cutting appliances to change their angle in altitude. These and other objects of this invention 35 will, however, hereinafter more fully appear.

In the accompanying drawings there is shown for purposes of illustration one form and a modification thereof which the invention may assume in practice.

40 In these drawings,—

Fig. 1 is a side elevational view of a coal mining apparatus having embodied therein an illustrative form of the improved adjustable supporting structure for the cutting appliances, parts being shown in vertical section to illustrate structural details.

45 Fig. 2 is a plan view of the apparatus shown in Fig. 1.

Fig. 3 is a horizontal sectional view taken substantially on line 3—3 of Fig. 1.

50 Fig. 4 is a vertical sectional view taken substantially on line 4—4 of Fig. 2.

Fig. 5 is a transverse sectional view taken substantially on line 5—5 of Fig. 4.

55 Fig. 6 is a vertical sectional view taken substantially on line 6—6 of Fig. 2.

Fig. 7 is a plan view of the mechanism shown in Fig. 6, parts being shown in horizontal section to illustrate details of construction.

Fig. 8 is a detail sectional view taken substantially on line 8—8 of Fig. 5.

Fig. 9 is a detail sectional view taken substantially on line 9—9 of Fig. 7.

Fig. 10 is a view similar to Fig. 3 and illustrating a modified form of construction.

Fig. 11 is a vertical sectional view taken on line 11—11 of Fig. 10.

Fig. 12 is a transverse sectional view with parts shown in plan taken substantially on line 12—12 of Fig. 11.

Fig. 13 is a vertical sectional view taken on a 15 plane corresponding to Fig. 6 and illustrating the forward end of the modified supporting structure.

Fig. 14 is a detail sectional view taken through the swinging mechanism for the cutting appliances.

20 In this illustrative construction there is shown a coal mining apparatus of the mounted, track cutting type generally comprising a truck frame 1 mounted on wheels 2 adapted to run along a mine trackway 3 and having supported on the forward end thereof the improved revoluble supporting structure generally designated 4 for the cutting appliances, the cutting mechanism being generally indicated at 5. Carried by the truck frame is a motor 6 which is adapted to drive 25 through mechanism which may be generally similar to that disclosed in the patent to Oldroyd 1,460,075, the truck wheels 2 and the cutting mechanism 5, and as hereinafter described, the improved adjusting mechanism for the adjustable supporting structure 4.

30 Now referring to the improved adjustable supporting structure, it will be noted that the neck structure is indicated at 7 and this neck structure is supported within the forward end of the truck frame to rotate on an axis which is horizontal and parallel to the length of the apparatus. Said neck structure has a cylindrical neck 8 which rests in a horizontal longitudinal bearing 9 formed in an upstanding frame structure 10 at the forward end of the truck. The mechanism for rotating the neck 8 within its bearing 9 to revolve the adjustable supporting structure 4 about the neck axis to vary the cutting position of the cutting mechanism 5 may be of the same 35 general character as that described in the patent to Oldroyd 1,456,930 and herein includes a worm wheel 11 seated on the neck at the rear of the frame 10 and meshing with a worm wheel 12 driven, through suitable operator-controlled con- 40 45 50 55

nections, by the motor 6. As the specific construction of this mechanism for revolving the adjustable cutter supporting structure 4 does not per se enter into this invention, further detail description of the same is unnecessary other than to state that by rotating the worm wheel 11 the entire neck structure is rotated about the neck axis. Again referring to the improved adjustable supporting structure 4, it will be observed that formed on the neck are forwardly projecting side arms or side walls 13, 13 which are parallel to each other and parallel to and equidistant from the axial line of the neck. In each of said walls is a bearing 14 in alignment with the other of said bearings on a line which is perpendicular to and intersects the axial line of the neck. In said bearings 14, 14 is mounted a shaft 15. Forward of the neck structure is a single swingable supporting arm or link member 16 which constitutes the sole connection between the revoluble neck structure and the cutting mechanism 5 and having at its rear end projections 17 each of which overlaps the inner face of one of the walls 13 of the neck structure as shown in Fig. 3. These projections 17 are mounted on the bearing sleeves 14, 14 carried by the side walls 13, 13 of the neck structure. The shaft 15 extends through the projections 17 and side walls 13 within the bearings 14 to form journals for the link member or arm 16, said journals being on an axial line which is perpendicular to and intersects the axial line of the neck. At its forward end the arm or link member 16 has a pair of parallel projections 18, 18 each of which is in approximately the plane 35 of the corresponding projections 17 and each of these projections 18 overlaps the inner face of one of a pair of side arms or projections 19, 19 formed on the cutter head frame 20. Supported within each of the projections 18 is a bearing sleeve 21 and mounted within these bearing sleeves is a shaft 22 parallel to the shaft 15. These bearing sleeves 21 in which the shaft 22 is supported project outwardly through the side arms 19 formed on the cutter head frame and form a pivotal mounting for the cutter head frame as herein-after described. Pivotedly mounted on the cutter head frame 20 about an axis perpendicular to the axial line of the neck is an elongated plane cutter bar 23 carrying on its margin an endless cutter bit carrying cutter chain 24, this cutter bar being swingable about its axis in planes parallel to the neck axis and in planes including the neck axis. The driving connections between the motor 6 and the cutting mechanism herein comprise a horizontal longitudinally extending shaft 25 alined with and connected to, as by a coupling 26, the motor shaft 27. A neck shaft 28 is located in the neck on the axial line of the neck and has keyed thereto at its rear end a clutch element 28^a which is connectible by a shiftable clutch element 28^b to the shaft 25 as shown in Fig. 1. Fixed to the forward end of the neck shaft 28 is a bevel gear 29 meshing with and driving a bevel gear 30 loosely mounted on the shaft 15. On the arm or link member 16 are two bearings 31, 31 which are on an axial line which intersects the axial lines of the shafts 15 and 22 and the axial line of the neck. In said bearings is journaled a transmission shaft 32 which has fixed thereto at its rear end a bevel gear 33 meshing with and driven by the bevel gear 30 as shown in Fig. 3. Fixed to the forward end of the shaft 32 is a bevel gear 34 meshing with and driving a bevel gear 35 fixed to the shaft 22. Journaled within the cutter head frame 20, as shown in Fig. 6, is a shaft 36 having fixed thereto at its rear end a bevel gear 37 meshing with and driven by the bevel gear 35 (see Fig. 3). Fixed to the forward end of the shaft 36 is a bevel gear 38 meshing with a bevel gear 39 keyed to a shaft 40 suitably journaled within the cutter head frame and arranged with its axis perpendicular to the axial line of the neck in various positions including horizontal cutting positions. Keyed to the shaft 40 at 42 is a chain sprocket 43 which engages 10 and drives the cutter chain 24 in the manner well understood in the art. The cutter head comprises a body 44 and a cap member 45 which is suitably secured to the body. The two pairs of side arms or projections 19, 19 are formed on the body 44. The body extends forwardly and has a bearing 46 which receives one end of the shaft 40 as shown in Fig. 6. The cap member extends forwardly and has a bearing 47 in alignment with the bearing 46 and also receives the shaft 20 49. The cutter bar support 48 has a cap plate 49 which surrounds the bearing 47 of the cap member. It will thus be seen that the cutter support is hinged to turn on the axial line of the shaft 40. A worm wheel 50 loosely surrounds the bearing 46 and rests against a supporting plate 51 and bears against the horizontal part of the support and is adapted to be engaged to the cutter support by a latch mechanism to be herein-after described. It will thus be seen that the worm wheel 50 is arranged concentric with the shaft 40 and meshing with this worm wheel is a worm 52 fixed to a transverse shaft 53. The shaft 53 is suitably journaled in bearing sleeves 54 supported within projections 54^a, 54^b formed integral with the side arms 19, 19. The mechanism for rotating the worm in either of opposite directions to swing the cutter bar in opposite directions about its pivot at a slow speed appropriate for cutting herein comprises a bevel gear 55 fixed to the shaft 22 and meshing with reverse bevels 56, 57 loosely journaled on an inclined shaft 58. The shaft 58 is suitably journaled within a gear housing 58^a secured to the side of the cutter head frame 20. Splined to this shaft is a jaw clutch member 59 which is adapted to connect alternatively the reverse bevels 56, 57 to the shaft 58. Keyed to the shaft 58 is a worm 60 meshing with a worm wheel 61 keyed to the shaft 53 (see Fig. 9) which drives the worm 50 52 meshing with the bar swinging worm wheel 50. It will thus be seen that the cutter bar may be swung in its plane about its pivot and that the cutter chain may be driven irrespective of the adjustment of the supporting structure about the neck axis or the plane of operation of the cutter bar. The latch mechanism for locking the cutter bar support to the worm wheel 50 or for releasing the cutter bar support for free swinging movement about the axis of the shaft 40 herein comprises a latch 62 pivotally mounted at 62^a on the cutter bar support. The cap plate 51 is provided with a notch 63 for receiving the latch and allows said latch to rest between two teeth of the worm wheel 50. Suitable means 64 is provided for 65 maintaining the latch 62 in its locking position. It will thus be seen that when the latch is in its locking position as shown in Fig. 6 and the worm wheel 50 is rotated through the mechanism described above, the cutter bar is swung with the 70 worm wheel at a slow cutting speed. When the latch 62 is swung downwardly and released from the teeth of the worm wheel and the notch 63 in the cap plate, the cutter bar is free to swing relative to the worm wheel 50. This latch mech- 75

anism may be the same as that described in the patent to Oldroyd 1,460,076.

The improved mechanism for adjusting the supporting structure 4 to position the cutter bar 23 into parallel planes while maintaining the cutter bar parallel to the neck axis herein comprises worm racks or gear segments 65 formed on the projections or side walls 13, 13 of the neck structure 7. Meshing with these worm racks or gear segments are parallel worms 66, 66 keyed to parallel shafts 67, 67 suitably journaled within the arm 16 and in the present construction arranged with their axes perpendicular to the axial line of the shaft 15. Keyed to the shafts 67, 67 are worm wheels 68, 68 (see Fig. 5) which mesh with worms 69, 69 keyed to a transverse shaft 10 likewise suitably journaled within the arm 16. Keyed to the shaft 10 intermediate its ends is a worm wheel 71 meshing with a worm 72 loosely mounted on the transmission shaft 32. This worm is connectible to the shaft 32 by a jaw clutch 73 having suitable shipper mechanism 74 including a transverse shaft 75 carrying at its ends operating handles 18 located at the opposite sides of the arm. Also formed on the projections, 19, 19 on the cutter head frame 20 are worm racks or gear segments 77, 77 with which mesh worms 78, 78 keyed to parallel shafts 79, 79 suitably journaled within the forward end of the arm 16. Keyed to these shafts are wormwheels 80, 80 with which mesh forms 81, 81 keyed to a transverse shaft 82 likewise suitably journaled within the arm 16. Fixed to this shaft intermediate its ends is a worm wheel 83 with which meshes a worm 84 loosely journaled on the shaft 32 and connectible to the shaft by a jaw clutch 85 similar to the clutch 73 and having similar operating mechanism including handles 86 arranged adjacent the handles 78, 79 heretofore described.

From the foregoing description it will be evident that when the worms 72, 84 are connected to the shaft 32 and the shaft 32 is connected to the motor, the worms 66, 66 meshing with the worm racks 65, 65 and the worms 78, 78 meshing with the worm racks 77, 77 are simultaneously driven, causing the arm 16 to be swung about the axis of the shaft 15 in one direction while the cutter head is swung about the axis of the shaft 22 in the opposite direction, the speeds of adjustment being so proportioned that as the cutter arm and cutter head are swung simultaneously about their respective axes, the cutter bar 23 is maintained at all times parallel to the axial line of the neck. It will be evident that when the clutch 73 is disconnected and the clutch 85 connected, the cutter head frame may be swung about the axis of the shaft 22 while the arm 16 remains stationary, thereby enabling the cutter bar to be tilted about an axis transverse to its length. It will also be evident that when the clutch 73 is connected and the clutch 85 released the supporting arm may be swung about its axis while the cutter head frame remains stationary as to movement about its axis. The worms 66, 66 and 78, 78 meshing with the worm racks on the neck structure and cutter head respectively, are self-locking and maintain automatically the arm and cutter head in their different positions of adjustment.

In the modified construction shown in Figs. 10 to 14 inclusive the supporting arm is indicated at 85, the revoluble neck structure at 96 and the cutter head at 97. In this form of the invention the driving connections between the motor and the cutting mechanism are the same as those

in the form described above and therefore a repetition of the description of the same is unnecessary. In this form of the invention, instead of forming the worm gear segments 65, 65 and 77, 77 on the neck structure and cutter head respectively, these worm gear segments are formed on the opposite ends of the arm 95 and are indicated at 98, 98 and 99, 99. The gear segments or racks 98, 98 are formed on projections 100, 100 formed on the rear end of the arm 95 and overlap the outer faces of parallel side walls 101, 101 formed on the neck structure. The worm racks or gear segments 99, 99 are formed on projections 102, 102 formed on the forward end of the arm 95 and overlap the outer faces of projections 103, 103 formed on the cutter head 97. Carried by the neck structure 96 are parallel worms 104, 104 meshing with the worm racks 98, 98 and fixed to parallel shafts 105, 105. Keyed to these shafts are worm wheels 106, 106 with which mesh worms 107, 107 fixed to a transverse shaft 108 suitably journaled within the frame of the neck structure 96. Connectible to the shaft 108 by a jaw clutch 109 is a spur gear 110 meshing with an idler gear 111 which in turn meshes with a spur gear 112 herein formed integral with and driven by the bevel gear 30 of the cutter chain driving mechanism. Meshing with the worm racks 99, 99 formed on the forward end of the arm 95 are worms 113, 113 keyed to parallel shafts 114, 114 suitably journaled within the cutter head frame. Fixed to these shafts are worm wheels (one of which is indicated at 115 in Fig. 13) and meshing with these worm wheels are worms (one of which is indicated at 116 in Fig. 13). These worms are fixed to a transverse shaft 117 suitably journaled within the cutter head frame. Connectible to this shaft and loosely journaled thereon is a spur gear 118 meshing with an idler gear 119 which in turn meshes with a spur gear 120 herein driven by the bevel gear 35. In this form of the invention the mechanism for swinging the cutter bar, generally designated 121, is substantially the same as that in the form described above and includes mechanism for swinging the cutter bar about its pivot in either of opposite directions at a cutting speed, (see Figs. 10 and 14). It will thus be seen that when the spur gears 110 and 113 are connected to their respective shafts 108 and 117 the arm 95 may be swung about the axis of the shaft 15 in one direction while the cutter head is swung simultaneously about the axis of the shaft 22, the parts being so proportioned as to maintain the cutter bar at all times in planes parallel to the axial line of the neck. Independent adjustment of the arm and cutter head may be had simply by disconnecting one or the other of the spur gears 110 and 113 from its respective shaft, thereby permitting the cutter bar to be tilted out of parallelism with the neck axis about an axis transverse to the direction of its length.

The general mode of operation of the improved mining apparatus is as follows. The apparatus is propelled about the mine at a relatively high transport speed under the propulsion of the truck wheels while the truck wheels are driven at a relatively slow speed appropriate for cutting to propel the apparatus along the trackway to effect sumping and withdrawal movements of the cutter bar in the manner clearly described in the Oldroyd Patent No. 1,460,075. The cutter bar may be adjusted in any desired position between the mine roof and the mine floor simply by actuating the clutches to connect the worms in

driving relation with the motor to effect swinging of the supporting arm and cutter head about their respective pivots, the worm gearing effecting swinging of the supporting arm and cutter head 5 simultaneously in opposite directions to maintain the plane of the cutter bar at all times parallel to the axial line of the neck. The cutter bar may be adjusted in any desired position about the neck axis simply by connecting the worm 12 10 in driving relation with the motor to cause the neck structure to be revolved in its bearing. The cutter chain may be connected in driving relation with the motor simply by connecting the clutch 23^b and the cutter bar may be swung about its 15 pivot by actuating the clutch 59 to connect one or the other of the reverse bevels 56, 57 to the shaft 58. It will thus be seen that the cutter bar may be positioned to cut horizontal kerfs in parallel planes above and below the neck axis and vertical kerfs in parallel planes at either side of the neck axis. As the operation of a mounted track cutter of the type disclosed herein is well known to those skilled in the art, detailed description of the various operations of the apparatus is considered unnecessary other than to state that 25 arcwall cuts may be made at the level of the mine bottom in front of the end of the trackway, that horizontal kerfs may be cut at the level of the mine roof or in any intermediate plane between 30 the mine roof and mine floor, and that vertical or shear cuts may be made in any position between the sides of the entry.

As a result of this invention, it will be noted that an improved mining apparatus is provided 35 having an improved adjustable supporting structure for the cutting appliances whereby the latter may be easily adjusted in any desired position. It will further be noted that by providing the single supporting arm or link member for the cutting mechanism and by providing the separate 40 motor operated devices for swinging the arm about its hinge and swinging the cutter head relative to the arm it is possible to obtain an extremely flexible and wide range of adjustment, 45 while at the same time eliminating all complicated adjusting mechanism, it also being possible to tilt the cutter bar relative to the supporting arm at various angles to suit different cutting conditions. These and other uses and advantages of the improved mining apparatus will be clearly apparent 50 to those skilled in the art.

While there is in this application specifically described one form and a modification thereof of which this invention may assume in practice, it will be 55 understood that this form and modification thereof of the same is shown for purposes of illustration and that the invention may be modified and embodied in various other forms without departing from its spirit or the scope of the appended claims.

What I claim as new and desire to secure by Letters Patent is:

1. In a mining apparatus a support, kerf cutting mechanism including a pivoted cutter bar 65 and an adjustable supporting structure intervening said support and cutting mechanism comprising but a single arm hinged to said support to swing upwardly and downwardly about an axis at right angles to the longitudinal axis of said support and on which said cutting mechanism is pivotally mounted, said arm constituting the sole supporting connection between said support and said cutting mechanism, and mechanism for swingingly adjusting said supporting structure 70 and cutting mechanism to position said cutter bar 75

into parallel planes while said bar is stationary as regards swinging on its own pivot and is always maintained parallel to a common straight line, said adjusting mechanism including means for swinging said arm and cutting mechanism about their pivots to move said cutter bar into aforesaid parallel planes. 5

2. In a mining apparatus, a wheeled truck, kerf cutting mechanism including a cutter bar support carrying a cutter bar, an adjustable supporting structure intervening said truck and cutting mechanism comprising but a single arm hinged to said truck to swing in longitudinal planes relative thereto upwardly and downwardly and on which said cutter bar support is pivotally mounted, said arm constituting the sole supporting connection between said truck and said cutting mechanism, and mechanism for simultaneously swinging said arm and cutter bar support about their respective pivots to adjust 10 said cutter bar into parallel horizontal planes while said bar is always maintained parallel to a common straight line, and means for operating said bar to cut a horizontal plane kerf in any of aforesaid parallel planes. 15

3. In a mining apparatus, a wheeled truck, kerf cutting mechanism including a cutter bar support and an adjustable supporting structure intervening said truck and cutting mechanism including an arm extending longitudinally of the truck and pivotally connected to said truck and on which said cutter bar support is pivotally mounted, said arm and support being swingable about parallel axes arranged at right angles to the longitudinal axis of the apparatus to move 20 the cutter bar into parallel planes, motor operated devices for swinging said arm about its pivot relative to said truck, and separate motor operated devices for swinging said bar support about its pivot relative to said arm. 25

4. In a mining apparatus, a wheeled truck, kerf cutting mechanism including a cutter bar support and an adjustable supporting structure intervening said truck and cutting mechanism including an arm extending longitudinally of the truck and pivotally connected to said truck and on which said cutter bar support is pivotally mounted, said arm and support being swingable about parallel axes arranged at right angles to the longitudinal axis of the apparatus to move 30 the cutter bar into parallel planes, motor operated devices for swinging said arm about its pivot relative to said truck, and separate motor operated devices for swinging said bar support about its pivot relative to said arm. 40

5. In a mining apparatus a wheeled truck, an arm pivotally mounted on the forward end of said truck and extending forwardly in advance of said truck, a cutter bar support pivotally mounted on the outer extremity of said arm and having a cutter bar pivotally mounted thereon to swing relative thereto, said arm and bar support being swingable about parallel axes arranged at right angles to the longitudinal axis of the apparatus, motor operated devices for swinging said arm about its pivot relative to said truck, and motor operated devices for swinging said cutter 45 bar support relative to said arm being operable independently of said arm swinging devices. 50

6. In a mining apparatus, a wheeled truck, an arm pivotally mounted on the forward end of said truck and extending forwardly in advance of said truck, a cutter bar support pivotally mounted on 55

the outer extremity of said arm and having a cutter bar pivotally mounted thereon to swing relative thereto, said arm and cutter support being swingable in longitudinally extending vertical planes relative to said truck, motor operated devices for swinging said arm about its pivot relative to said truck, and motor operated devices for swinging said cutter support about its pivot relative to said arm, said devices being operable simultaneously to swing said arm and cutter bar support in opposite directions to maintain the cutter bar at all times parallel to a common straight line.

7. In a mining apparatus, a wheeled truck, an arm pivotally mounted on the forward end of said truck to swing in longitudinal planes relative thereto and extending forwardly in advance of said truck, a cutter bar support pivotally mounted on the outer extremity of said arm and having a cutter bar pivotally mounted thereon, motor operated devices including intermeshing gearing for swinging said arm about its pivot relative to said truck, and motor operated devices including intermeshing gearing for swinging said cutter bar support about its pivot relative to said arm, said arm and said bar support being swingable about their pivots to move said cutter bar into parallel cutting positions in a wide range of positions in advance of the truck.

8. In a mining apparatus, a wheeled truck, an arm pivotally mounted on the forward end of said truck to swing in vertical planes extending longitudinally of said truck and extending forwardly in advance of said truck, a cutter bar support pivotally mounted on the outer extremity of said arm and having a cutter bar pivotally mounted thereon, motor operated devices including intermeshing gearing for swinging said arm about its pivot relative to said truck, and motor operated devices including intermeshing gearing for swinging said cutter bar support about its pivot relative to said arm, said devices being operable simultaneously to swing said arm and cutter bar support in opposite directions to maintain the cutter bar at all times parallel to a common straight line.

9. In a mining apparatus, a wheeled truck, an arm pivotally mounted on the forward end of said truck to swing relative thereto about a horizontal axis extending transversely of the truck and extending forwardly in advance of said truck, a cutter bar support pivotally mounted on the outer extremity of said arm and having a cutter bar pivotally mounted thereon, motor operated devices including self-locking worm gearing for swinging said arm about its pivot relative to said truck, and motor operated devices including self-locking worm gearing for swinging said cutter bar support about its pivot relative to said arm.

10. In a mining apparatus, a wheeled truck, an arm pivotally mounted on the forward end of said truck to swing in a vertical direction relative thereto about a horizontal axis extending transversely of said truck and extending forwardly in advance of said truck, a cutter bar support pivotally mounted on the outer extremity of said arm and having a cutter bar pivotally mounted thereon, motor operated devices including self-locking worm gearing for swinging said arm about its pivot relative to said truck, and motor operated devices including self-locking worm gearing for swinging said cutter bar support about its pivot relative to said arm, said devices being operable simultaneously to swing said arm and cutter bar support in opposite directions to maintain the

cutter bar at all times parallel to a common straight line.

11. In a mining apparatus, a wheel mounted frame, an arm pivotally mounted on the forward end of said frame to swing in longitudinal planes relative thereto and extending forwardly in advance of said frame, a cutter bar support pivotally mounted on the outer extremity of said arm and having a cutter bar pivotally mounted thereon, motor operated devices for swinging said arm about its pivot relative to said frame including cooperating gear elements on said arm and frame, and motor operated devices for swinging said cutter bar support about its pivot relative to said arm including cooperating gear elements on said arm and cutter bar support, said arm and said bar support being swingable about their pivots to move said cutter bar into parallel cutting positions.

12. In a mining apparatus, kerf cutting mechanism including a cutter bar, and an adjustable supporting structure therefor including a support revolvably mounted for rotation about a longitudinal axis, and, intervening said support and cutting mechanism, but a single arm pivoted to swing in longitudinal planes relative to said support and on the outer extremity of which said cutting mechanism is pivotally mounted, said arm constituting the sole supporting connection between said support and said cutting mechanism, and mechanism for adjusting said supporting structure to move said cutter bar toward and from said longitudinal axis into parallel planes and also in an orbit about said longitudinal axis while said cutter bar is always maintained parallel to said longitudinal axis.

13. In a mining apparatus, kerf cutting mechanism including a cutter bar support, and an adjustable supporting structure therefor including a support revolvably mounted to turn about a longitudinal axis, and, intervening said second mentioned support and said cutting mechanism, but a single arm hinged to swing relative to said second support and on which said cutter bar support is pivotally mounted, said arm constituting the sole supporting connection between said second mentioned support and said cutting mechanism, and mechanism for simultaneously swinging said arm and said cutter bar support about their respective pivots to adjust said cutter bar through a series of parallel planes and for revolving said supporting structure about said longitudinal axis to move said cutter bar orbitally about said axis while said bar is always maintained parallel to said axis.

14. In a mining apparatus, a wheeled truck, kerf cutting mechanism including a cutter bar support, and an adjustable supporting structure revolvably mounted on said truck about a longitudinal axis and extending between said truck and said cutting mechanism, said structure including an arm pivoted to swing in longitudinal planes relative to said truck and on the outer extremity of which said cutter bar support is pivotally mounted, said arm and bar support being swingable about parallel axes to move the cutter bar toward and from said longitudinal axis into parallel cutting positions, motor operated devices for swinging said arm about its pivot, and separate motor operated devices for swinging said cutter bar support about its pivot relative to said arm.

15. In a mining apparatus, a wheeled truck, kerf cutting mechanism including a cutter bar support, and an adjustable supporting structure

revolubly mounted on said truck about a longitudinal axis and extending between said truck and said cutting mechanism, said structure including an arm pivoted to swing relative to said truck and on the outer extremity of which said cutter bar support is pivotally mounted, said arm and bar support being swingable about parallel axes to move the cutter bar toward and from said longitudinal axis into parallel cutting positions, 10 motor operated devices for swinging said arm about its pivot, and separate motor operated devices for swinging said cutter bar support about its pivot relative to said arm, said devices for swinging said cutter bar support being operable 15 independently of said arm swinging devices.

16. In a mining apparatus, a wheeled truck, a frame mounted on said truck for rotation about a longitudinal axis, an arm pivotally mounted on said frame to swing relative thereto about an axis 20 at right angles to the frame axis and extending forwardly in advance of said truck, a cutter bar support pivotally mounted on the outer extremity of said arm and having a cutter bar pivotally mounted thereon, said arm constituting the sole 25 supporting connection between said rotatable frame and said bar support, devices for rotating said frame relative to said truck to adjust said arm about said longitudinal axis, devices for swinging said arm about its pivot relative to 30 said frame, and devices for swinging said cutter bar support about its pivot relative to said arm.

17. In a mining apparatus, a wheeled truck, a frame mounted on said truck for rotation about a longitudinal axis, an arm pivotally mounted on 35 said frame to swing relative thereto about an axis at right angles to the frame axis and extending forwardly in advance of said truck, a cutter bar support pivotally mounted on the outer extremity of said arm and having a cutter bar pivotally mounted thereon, said arm constituting the sole supporting connection between said rotatable frame and said bar support, devices for rotating said frame relative to said truck to adjust said arm about said longitudinal axis, devices 40 for swinging said arm about its pivot relative to said frame, and devices for swinging said cutter bar support about its pivot relative to said arm, said arm swinging and support swinging devices being operable simultaneously to swing 45 said arm and support in opposite directions to maintain said cutter bar at all times parallel to the axis of said frame.

18. In a mining apparatus, a wheeled truck, an arm pivotally mounted on the forward end 55 of said truck and extending forwardly in advance of said truck, a cutter bar support pivotally mounted on the outer extremity of said arm and having a cutter bar pivotally mounted thereon, said arm and bar support being swingable 60 about their respective axes in vertical planes extending longitudinally of said truck, motor operated devices for swinging said arm about its pivot including a rack carried at the rear end of said arm and a gear meshing with said rack, and 65 motor operated devices for swinging said cutter bar support about its pivot relative to said arm including a rack carried on the forward end of said arm, and a gear meshing with said rack.

19. In a mining apparatus, a wheeled truck, a 70 single arm pivotally mounted on the forward end of said truck to swing in longitudinal planes relative thereto and extending forwardly in advance of said truck, a cutter bar support pivotally mounted on the outer extremity of said arm and 75 having a cutter bar pivotally mounted thereon,

said arm constituting the sole support between said truck and said cutter bar support, and motor operated devices for swinging said arm about its pivot and for swinging said bar support relative to said arm to move the cutter bar into 5 parallel planes while the cutter bar is always maintained parallel to a common straight line.

20. In a mining apparatus, a wheeled truck, an arm pivotally mounted on the forward end of said truck, kerf cutting mechanism supported at 10 the forward end of said arm and including a forwardly projecting horizontal kerf cutter, and devices carried by said arm for swinging said arm about its pivot to adjust said cutter bar into parallel planes while said cutter bar is maintained 15 always parallel to a horizontal plane.

21. In a mining apparatus, a support, kerf cutting mechanism including a cutter bar, an adjustable supporting means between said support and said cutting mechanism including a supporting 20 structure pivotally mounted on said support to swing in longitudinal planes relative thereto, a cutter bar support pivotally mounted on the outer extremity of said supporting structure for swinging movement about an axis parallel to the supporting structure axis, said supporting structure and said bar support being swingable about their respective axes to move said cutter bar into parallel cutting positions, motor operated devices for swinging said supporting structure about its 25 axis relative to said support, and separate motor operated devices for swinging said cutter bar support relative to said supporting structure while the latter remains stationary.

22. In a mining apparatus, a support, kerf cutting mechanism including a cutter bar, an adjustable supporting means between said support and said cutting mechanism including a supporting structure pivotally mounted on said support to swing in longitudinal planes relative thereto about 35 a horizontal axis extending transversely of said support, a cutter bar support pivotally mounted on the outer extremity of said supporting structure for swinging movement about an axis parallel to the supporting structure axis, motor operated devices for swinging said supporting structure about its axis relative to said support, and separate motor operated devices for swinging said cutter bar support relative to said supporting structure while the latter remains stationary, said motor 40 operated devices being simultaneously operable to swing said supporting structure and bar support in opposite directions about their respective axes to position said bar into parallel planes while said bar is always maintained parallel to a 45 common straight line.

23. In a mining apparatus, a support, a frame member mounted on said support for rotation relative thereto about a longitudinal axis, kerf cutting mechanism including a cutter bar, an adjustable supporting means between said rotatable frame member and said cutting mechanism including a supporting structure pivotally mounted on said frame member, a cutter bar support pivotally mounted on the outer extremity of said supporting structure for swinging movement relative thereto about an axis parallel to the supporting structure axis, said supporting structure and said bar support being swingable about their respective axes to move said cutter bar into parallel cutting positions, motor operated devices for swinging said supporting structure about its axis relative to said support, and separate motor operated devices for swinging said cutter bar sup- 70 75 75

port relative to said supporting structure while the latter remains stationary.

24. In a mining apparatus, a support, a frame member mounted on said support for rotation relative thereto about a longitudinal axis, kerf cutting mechanism including a cutter bar, an adjustable supporting means between said rotatable frame member and said cutting mechanism including a supporting structure pivotally mounted on said frame member, a cutter bar support pivotally mounted on the outer extremity of said supporting structure for swinging movement relative thereto about an axis parallel to the supporting structure axis, motor operated devices for swinging said supporting structure about its axis relative to said support, and separate motor operated devices for swinging said cutter bar support relative to said supporting structure while the latter remains stationary, said motor operated devices being simultaneously operable to swing said supporting structure and bar support in opposite directions about their respective axes to position said bar in parallel planes while said bar is always maintained parallel to a common straight line.

25. In mining apparatus, a portable base, kerf cutting mechanism including a cutter bar and a cutter bar support relative to which said bar is swingable, an arm pivotally mounted on the forward end of said base and on the outer extremity of which said cutter bar support is pivotally mounted for swinging movement about an axis parallel to the axis of swinging movement of said arm, a motor on said base, and devices driven by said motor including gearing and controlling clutches carried by said arm for simultaneously swinging said arm and cutter bar support about their respective axes.

26. In a mining apparatus, a portable base, kerf cutting mechanism including a cutter bar and a cutter bar support, an arm pivotally mounted on the forward end of said base and on the outer extremity of which said cutter bar support is pivotally mounted for swinging movement about an axis parallel to the axis of swinging movement of said arm, a motor on said base, and devices driven by said motor including gearing and controlling clutches carried by said arm for simultaneously swinging said arm and cutter bar support about their respective axes to position said cutter bar into parallel planes while said bar is always maintained parallel to a common straight line.

27. In a mining apparatus, a portable base, a support mounted on said base for rotation relative thereto about a longitudinal axis, kerf cutting mechanism including a cutter bar and a cutter bar support, a single arm pivotally mounted on said rotatable support and extending forwardly in advance of said base and on the outer extremity of which said cutter bar support is pivotally mounted for swinging movement about an axis parallel to the axis of swinging movement of said arm, said arm constituting the sole supporting connection between said rotatable support and said bar support, and mechanism for swinging said arm and cutter bar support about their respective axes to move said bar toward and from the axis of said rotatable support into parallel cutting positions.

28. In a mining apparatus, a portable base, a support mounted on said base for rotation relative thereto about a longitudinal axis, kerf cutting mechanism including a cutter bar and a cutter bar support, a single arm pivotally mount-

ed on said rotatable support and extending forwardly in advance of said base and on the outer extremity of which said cutter bar support is pivotally mounted for swinging movement about an axis parallel to the axis of swinging movement of said arm, said arm constituting the sole supporting connection between said rotatable support and said bar support, and mechanism for swinging said arm and cutter bar support about their respective axes to position said cutter bar into parallel planes while said bar is always maintained parallel to a common straight line parallel to the axis of said rotatable support.

29. In a mining apparatus, a portable base, a support mounted on said base for rotation relative thereto about a longitudinal axis, kerf cutting mechanism including a cutter bar and a cutter bar support, a single arm pivotally mounted on said rotatable support and extending forwardly in advance of said base and on the outer extremity of which said cutter bar support is pivotally mounted for swinging movement about an axis parallel to the axis of swinging movement of said arm, said arm constituting the sole supporting connection between said rotatable support and said bar support, and mechanism for swinging said arm and cutter bar support about their respective axes to position said cutter bar into parallel planes while said bar is always maintained parallel to a common straight line parallel to the axis of said rotatable support, said bar support swinging mechanism being operable independently of said arm swinging mechanism to tilt said cutter bar out of parallelism with said common straight line.

30. In a mining apparatus, a portable base, a kerf cutter swingable relative to said base to cut a vertical kerf, and adjustable supporting means on said base for supporting said kerf cutter and adjustable to move said kerf cutter into parallel vertical cutting positions between the sides of said base and including a plurality of relatively adjustable supports, one mounted on the other and rotatable relative to the base about parallel vertical axes and motor operated devices for independently rotating said supports about their respective axes, either support swingable relative to the other while the latter remains stationary as regards swinging movement about its own axis.

31. In a mining apparatus, a portable base, a kerf cutter swingable relative to said base to cut a vertical kerf, and adjustable supporting means on said base for supporting said kerf cutter and adjustable to move said kerf cutter into parallel vertical cutting positions including positions between the sides of said base and laterally beyond the sides of said base and including a plurality of relatively adjustable supports, one mounted on the other and rotatable relative to the base about parallel vertical axes and motor operated devices for independently rotating said supports about their respective axes, either support swingable relative to the other while the latter remains stationary as regards swinging movement about its own axis.

32. In a mining apparatus, a wheeled truck, kerf cutting mechanism including a cutter bar support and a cutter bar pivotally mounted on said support, and an adjustable supporting structure intervening said truck and said cutting mechanism including an arm pivotally connected to said truck and on which said cutter bar support is pivotally mounted, said arm and support being swingable in longitudinal planes about par-

- allel axes and said cutter bar being swingable relative to said bar support about an axis at right angles to a line parallel to a line parallel to the pivotal axis of said bar support, motor operated devices for swinging said arm about its pivot relative to said truck, separate motor operated devices for swinging said support about its pivot relative to said arm, and means for swinging said cutter bar relative to said bar support.
33. In a mining apparatus, a wheeled truck, kerf cutting mechanism including a cutter bar support and a cutter bar pivotally mounted on said support, and an adjustable supporting structure intervening said truck and said cutting mechanism including an arm pivotally connected to said truck and on which said cutter bar support is pivotally mounted, said arm and support being swingable in longitudinal planes about parallel axes and said cutter bar being swingable relative to said bar support about an axis at right angles to a line parallel to a line parallel to the pivotal axis of said bar support, motor operated devices for swinging said arm about its pivot relative to said truck, separate motor operated devices for swinging said support about its pivot relative to said arm, said devices for swinging said cutter bar support relative to said arm being operable independently of said arm swinging devices, and means for swinging said cutter bar relative to said bar support.
34. In a mining apparatus, kerf cutting mechanism including a cutter bar, a support revolvably mounted for rotation about a longitudinal axis, and, intervening said support and cutting mechanism, but a single arm pivoted to swing relative to said support about an axis at right angles to the longitudinal axis of said support and on the outer extremity of which said cutting mechanism is pivotally mounted, said arm constituting the sole supporting connection between said support and said cutting mechanism, and mechanism for adjusting said supporting structure to move said cutter bar into parallel planes toward and from said longitudinal axis and also in an orbit about said longitudinal axis while said cutter bar is always maintained parallel to said longitudinal axis, said adjusting mechanism including means for swinging said arm about its pivot to move said cutter bar into aforesaid parallel planes.
35. In a mining apparatus, a wheeled truck, kerf cutting mechanism including a cutter bar support and a cutter bar on said support, and an adjustable supporting structure revolvably mounted on said truck about a longitudinal axis and extending between said truck and said cutting mechanism, said structure including an arm pivoted to swing relative to said truck about an axis at right angles to the longitudinal axis of said truck and on the outer extremity of which said cutter bar support is pivotally mounted, said arm and bar support being swingable about parallel axes to move said cutter bar into parallel planes, motor operated devices for swinging said arm about its pivot, and separate motor operated devices for swinging said cutter bar support about its pivot relative to said arm.
36. In a mining apparatus, a wheel truck, kerf cutting mechanism including a cutter bar support and a cutter bar on said support, and an adjustable supporting structure revolvably mounted on said truck about a longitudinal axis and extending between said truck and said cutting mechanism, said structure including an arm pivoted to swing relative to said truck about an axis at right angles to the longitudinal axis of
- said truck and on the outer extremity of which said cutter bar support is pivotally mounted, said arm and bar support being swingable about parallel axes to move said cutter bar into parallel planes, motor operated devices for swinging said arm about its pivot, and separate motor operated devices for swinging said cutter bar support about its pivot relative to said arm, said devices for swinging said cutter bar support being operable independently of said arm swinging devices.
37. In a mining apparatus, a support, kerf cutting mechanism including a cutter bar, an adjustable supporting means between said support and said cutting mechanism including a supporting structure pivotally mounted on said support to swing in longitudinal planes relative thereto, a cutter bar support pivotally mounted on the outer extremity of said supporting structure for swinging movement about an axis parallel to the supporting structure axis, said cutter bar being pivotally mounted on said bar support about an axis at right angles to a line parallel to a line parallel to the pivotal axis of said bar support, motor operated devices for swinging said supporting structure about its axis relative to said support, and separate motor operated devices for swinging said cutter bar support relative to said supporting structure while the latter remains stationary.
38. In a mining apparatus, a support, a frame member mounted on said support for rotation relative thereto about a longitudinal axis, kerf cutting mechanism including a cutter bar, an adjustable supporting means between said rotatable frame member and said cutting mechanism including a supporting structure pivotally mounted on said frame member to swing relative thereto about an axis at right angles to the frame member axis, a cutter bar support pivotally mounted on the outer extremity of said supporting structure for swinging movement relative thereto about an axis parallel to the supporting structure axis, said cutter bar being pivotally mounted on said bar support about an axis at right angles to a line parallel to a line parallel to the pivotal axis of said bar support, motor operated devices for swinging said supporting structure about its axis relative to said support, and separate motor operated devices for swinging said cutter bar support relative to said supporting structure while the latter remains stationary.
39. In a mining apparatus, a portable base, a support mounted on said base for rotation relative thereto about a longitudinal axis, kerf cutting mechanism including a cutter bar and a cutter bar support on which said cutter bar is pivotally mounted to swing relative thereto, a single rigid arm pivotally mounted on said rotatable support to swing relative thereto about an axis transverse to the support axis and extending forwardly in advance of said base and on the outer extremity of which said cutter bar support is pivotally mounted for swinging movement about an axis parallel to the axis of swinging movement of said arm, said arm constituting the sole supporting connection between said rotatable support and said bar support, and mechanism for swinging said arm and cutter bar support about their respective axes.
40. In a mining apparatus, a portable base, kerf cutting mechanism mounted on said base and including a cutter bar support and a cutter bar on said support, an adjustable supporting structure intervening said base and said cutting

mechanism including an elongated arm extending forwardly lengthwise of the apparatus and in advance of said base, said arm being pivotally connected to said base and on the outer extremity of which said cutter bar support is pivotally mounted, said arm and support being swingable in longitudinal planes about parallel axes to move the cutter bar into parallel planes, motor operated devices for swinging said arm about its pivot relative to said base, and separate motor operated devices for swinging said bar support about its pivot relative to said arm.

41. In a mining apparatus, a portable base, kerf cutting mechanism mounted on said base and including a cutter bar support and a cutter bar on said support, an adjustable supporting structure intervening said base and said cutting mechanism including an elongated arm extending forwardly lengthwise of the apparatus and in advance of said base, said arm being pivotally connected to said base and on the outer extremity of which said cutter bar support is pivotally mounted, said arm and support being swingable in longitudinal planes about parallel axes to move the cutter bar into parallel planes, motor operated devices for swinging said arm about its pivot relative to said base, and separate motor operated devices for swinging said bar support about its pivot relative to said arm, said devices for swinging said cutter bar support relative to said arm being operable independently of said arm swinging devices.

42. In a mining apparatus, a portable base, an arm pivotally mounted on the forward end of said base and extending forwardly lengthwise of the apparatus and in advance of said base, a cutter bar support pivotally mounted on the outer extremity of said arm and having a cutter bar pivotally mounted thereon to swing relative thereto, said arm and support being swingable in longitudinal planes about parallel axes to move said cutter bar into parallel cutting positions, motor operated devices for swinging said arm about its pivot relative to said base, and motor operated devices for swinging said cutter support about its pivot relative to said arm.

43. In a mining apparatus, a portable base, an arm pivotally mounted on the forward end of said base and extending forwardly lengthwise of the apparatus and in advance of said base, a cutter bar support pivotally mounted on the outer extremity of said arm and having a cutter bar pivotally mounted thereon to swing relative thereto, said arm and support being swingable in longitudinal planes about parallel axes to move said cutter bar into parallel cutting positions, motor operated devices for swinging said arm about its pivot relative to said base, and motor operated devices for swinging said cutter bar support about its pivot relative to said arm, said devices being operable simultaneously to swing said arm and cutter bar support in opposite directions to maintain the cutter bar at all times parallel to a common straight line.

44. In a mining apparatus, a portable base, a frame mounted on said base and overhanging the forward end of said base, a single rigid elongated arm, pivotally mounted on said overhanging frame and extending forwardly longitudinally of the apparatus and in advance of the base, cutting mechanism including a swingable cutter bar pivotally mounted on the outer extremity of said arm, said arm being pivotally mounted on said base to swing relative thereto in longitudinally extending planes to move said cutter bar,

on adjustment of said cutting mechanism, into parallel planes, said arm constituting the sole supporting connection between said base and said cutting mechanism, and mechanism for swinging said arm relative to said base and for swinging said cutting mechanism about its pivot relative to said arm.

45. In a mining apparatus, a portable base, a frame mounted on said base, said frame overhanging the forward end of said base, kerf cutting mechanism mounted on said base and including a cutter bar support and a cutter bar on said support, and an adjustable supporting structure intervening said base and said cutting mechanism including an arm pivotally connected to said overhanging frame and on the outer extremity of which said cutter bar support is pivotally mounted, said arm and support being swingable about parallel axes spaced, longitudinally of the apparatus, a substantial distance apart to move the cutter bar into parallel planes, motor operated devices for swinging said arm about its pivot relative to said base, and separate motor operated devices for swinging said bar support about its pivot relative to said arm. 25

46. In a mining apparatus, a portable base, a frame mounted on said base, said frame overhanging the forward end of said base, kerf cutting mechanism mounted on said base and including a cutter bar support and a cutter bar on said support, and an adjustable supporting structure intervening said base and said cutting mechanism including an arm pivotally connected to said overhanging frame and on the outer extremity of which said cutter bar support is pivotally mounted, said arm and support being swingable about parallel axes spaced, longitudinally of the apparatus, a substantial distance apart to move the cutter bar into parallel planes, motor operated devices for swinging said arm about its pivot relative to said base, and separate motor operated devices for swinging said bar support about its pivot relative to said arm, said devices for swinging said cutter bar support relative to said arm being operable independently 45 of said arm swinging devices.

47. In a mining apparatus, a portable base, a frame mounted on said base, said frame overhanging the forward end of said base, an elongated arm mounted on said overhanging frame and extending forwardly lengthwise of the apparatus and in advance of said base, a cutter bar support pivotally mounted on the outer extremity of said arm and having a cutter bar pivotally mounted thereon to swing relative thereto, said arm and bar support being swingable about parallel axes spaced, longitudinally of the apparatus, a substantial distance apart to move said cutter bar into parallel cutting positions, motor operated devices for swinging said arm about its pivot relative to said base, and motor operated devices for swinging said cutter bar support about its pivot relative to said arm. 60

48. In a mining apparatus, a portable base, a support mounted on the forward end of said base for rotation relative thereto about a longitudinal axis, an elongated arm pivotally mounted on said rotatable support and extending forwardly lengthwise of the apparatus and in advance of said base, said arm being swingable in longitudinal planes relative to said base to move said cutter bar for adjustment into parallel cutting positions, a cutter bar support mounted on the outer extremity of said arm, a cutter bar pivotally mounted on said support to swing relative 75

thereto, and motor operated devices for independently swinging said arm relative to said rotatable support and for swinging said cutter bar support relative to said arm, and motor operated devices for rotating said rotatable support relative to said base.

49. In a mining apparatus, a portable base, an elongated arm structure pivotally mounted on said base to swing in longitudinal planes relative thereto, a cutter bar support pivotally mounted on the outer extremity of said arm structure, a cutter bar pivotally mounted on said bar support to swing relative thereto, and motor operated devices for swinging said arm structure about its pivot and for swinging said cutter bar support relative to said arm structure to move said cutter bar into parallel cutting positions, said cutter bar support being swingable relative to said arm structure while the latter remains stationary.

50. In a mining apparatus, a portable base, an elongated arm structure pivotally mounted on said base to swing in longitudinal planes relative thereto, a motor mounted on said base and relative to which said arm structure is swingable, a cutter bar support pivotally mounted on the outer extremity of said arm structure, a cutter bar pivotally mounted on said bar support to swing relative thereto, and devices driven by said motor for swinging said arm structure relative to said base and said bar support relative to said arm structure to move said cutter bar into parallel cutting positions, said bar support being swingable relative to said arm structure while the latter remains stationary.

51. In a mining apparatus, a portable base, an elongated arm structure pivotally mounted on said base to swing in longitudinal planes relative thereto, a motor mounted on said base and relative to which said arm structure is swingable, a cutter bar support pivotally mounted on the outer extremity of said arm structure, a cutter bar pivotally mounted on said bar support to swing relative thereto, devices driven by said motor for swinging said arm structure relative to said base and said bar support relative to said arm structure to move said cutter bar into parallel cutting positions, said bar support being swingable relative to said arm structure while the latter remains stationary, and devices driven by said motor for swinging said cutter bar about its pivot relative to said bar support.

52. In a mining apparatus, a portable base, a support carrying a kerf cutter and an adjustable supporting structure intervening said base and kerf cutter support comprising but a single arm hinged to the forward end of the base to swing about an axis at right angles to the longitudinal axis of the base and on which said kerf cutter support is pivotally mounted, said arm constituting the sole supporting connection between said kerf cutter support and said base, and mechanism for adjusting said supporting structure and kerf cutter support to position said kerf cutter into parallel planes, said adjusting mechanism including means for swinging said arm and support about their pivots to move said kerf cutter into aforesaid parallel planes.

53. In a mining apparatus, a portable base, a support carrying a kerf cutter and an adjustable supporting structure intervening said base and kerf cutter support comprising but a single arm hinged to the forward end of the base to swing about an axis at right angles to the longitudinal axis of the base and on which said kerf cutter sup-

port is pivotally mounted, said arm constituting the sole supporting connection between said kerf cutter support and said base, and mechanism for adjusting said supporting structure and kerf cutter support to position said kerf cutter into parallel planes including planes adjacent the mine floor and parallel planes a substantial distance above the top of said base, said adjusting mechanism including means for swinging said arm and support about their pivots to move said kerf cutter into aforesaid parallel planes.

54. In a mining apparatus, a portable base, a single rigid arm pivotally mounted on said base to swing in a vertical direction relative thereto about an axis extending transversely of said base, a cutter support pivotally mounted on the outer extremity of said arm to swing relative thereto about an axis parallel with the arm pivot axis, a horizontal kerf cutter pivotally mounted on said cutter support, and means for swinging said arm relative to said base and said cutter support relative to said arm to move said kerf cutter into parallel horizontal planes including horizontal planes above and below said base while the kerf cutter at all times remains in a horizontal cutting position.

55. In a mining apparatus, a portable base, a single rigid arm pivotally mounted on said base to swing in a vertical direction relative thereto about an axis extending transversely of said base, a cutter support pivotally mounted on the outer extremity of said arm to swing relative thereto about an axis parallel with the arm pivot axis, a horizontal kerf cutter pivotally mounted on said cutter support, and means for swinging said arm relative to said base and said cutter support relative to said arm to move said kerf cutter into parallel horizontal planes including horizontal planes adjacent the mine floor and horizontal planes a substantial distance above the top of said base while the kerf cutter at all times remains in a horizontal cutting position.

56. In a mining apparatus, a portable base, an arm pivotally mounted on said base to swing in a vertical direction relative thereto about an axis extending transversely of said base, said arm extending longitudinally of said base a substantial distance in advance of said base, a cutter support pivotally mounted on the outer extremity of said arm to swing relative thereto about an axis parallel with the arm pivot axis, said cutter support being swingable through at least 90° relative to said arm, a kerf cutter pivotally mounted on said cutter support to swing relative thereto, and means for swinging said arm and support about their respective axes.

57. In a mining apparatus, a portable base, an arm pivotally mounted on said base to swing in a vertical direction relative thereto about an axis extending transversely of said base, said arm extending longitudinally of said base a substantial distance in advance of said base, a cutter support pivotally mounted on the outer extremity of said arm to swing relative thereto about an axis parallel with the arm pivot axis, said cutter support being swingable through substantially 180° relative to said arm, a kerf cutter pivotally mounted on said cutter support to swing relative thereto, and means for swinging said arm and support about their respective axes.

58. In a mining apparatus, a portable base, a support mounted on said base for rotation about a longitudinal axis, an arm structure pivotally mounted on said rotatable support to swing relative thereto about an axis transverse to the sup-

port axis, a cutter frame mounted on the outer extremity of said arm structure and to which the arm structure is pivotally connected, a kerf cutter carried by said cutter frame, means for rotat-
5 ing said rotatable support to move the arm struc-
ture and cutter frame about the axis of said ro-
tatable support to adjust said kerf cutter into
horizontal and vertical cutting positions, and
means for swinging said arm structure and ad-
10 justing said cutter frame while said rotatable
support remains stationary as to rotation about
its own axis to move the kerf cutter through par-
allel planes from a point at a substantial distance
15 to one side of said rotatable support axis to a
point at a substantial distance to the other side
of said rotatable support axis.

59. In a mining apparatus, a portable base, a support mounted on said base for rotation about a longitudinal axis, an arm structure pivotally mounted on said rotatable support to swing relative thereto about an axis transverse to the support axis, a cutter frame mounted on the outer extremity of said arm structure and to which the arm structure is pivotally connected, a kerf cutter carried by said cutter frame, means for rotating said rotatable support to move the arm structure and cutter frame about the axis of said rotatable support to adjust said kerf cutter into horizontal and vertical cutting positions, and
20 means for swinging said arm structure and ad-
justing said cutter frame while said rotatable support remains stationary as to rotation about its own axis to move the kerf cutter through parallel planes from a point at a substantial distance
25 to one side of said rotatable support axis to a point at a substantial distance to the other side of said rotatable support axis, said kerf cutter moving through planes in which said support axis lies during adjustment thereof from one side
30 of said support axis to the other.

60. In a mining apparatus, a portable base, kerf cutting mechanism including a cutter sup-
port and an adjustable supporting structure in-
55 tervening said base and cutting mechanism in-
cluding an arm pivotally connected to said base and on which said cutter support is pivotally mounted, said arm and support being swingable about parallel axes arranged at right angles to the longitudinal axis of the apparatus to move
50 the kerf cutter into parallel planes, motor op-
erated means for swinging said arm about its pivot relative to said base, and separate motor operated means for swinging said cutter support about its pivot relative to said arm.

55. 61. In a mining apparatus, a portable base, kerf cutting mechanism including a cutter sup-
port and an adjustable supporting structure in-
60 tervening said base and cutting mechanism in-
cluding an arm pivotally connected to said base and on which said cutter support is pivotally mounted, said arm and support being swingable about parallel axes arranged at right angles to the longitudinal axis of the apparatus to move
65 the kerf cutter into parallel planes, motor op-
erated means for swinging said arm about its pivot relative to said base, and separate motor operated means for swinging said cutter support about its pivot relative to said arm, said means for swinging said cutter support relative to said arm being operable independently of said arm swinging means.

70 62. In a mining apparatus, a wheeled truck adapted to run along a mine trackway, a single rigid arm pivotally mounted on the forward end
75 of said truck to swing in a vertical direction rela-

tive thereto about a horizontal axis extending transversely of the apparatus in advance of the front truck wheel axes, a cutter support pivotally mounted on the outer extremity of said arm, a horizontal kerf cutter carried by said cutter sup-
5 port, and motor operated means for swinging said arm and cutter support about their respec-
tive axes to move the kerf cutter into parallel horizontal planes including horizontal planes above and below said truck.

10 63. In a mining apparatus, a wheeled truck adapted to run along a mine trackway, a single rigid arm pivotally mounted on the forward end of said truck to swing in a vertical direction relative thereto about a horizontal axis extending transversely of the apparatus in advance of the front truck wheel axes, a cutter support pivotally mounted on the outer extremity of said arm, a horizontal kerf cutter carried by said cutter support, and motor operated means for swing-
15 ing said arm and cutter support about their respec-
tive axes to move the kerf cutter into parallel horizontal planes including horizontal planes adjacent the mine floor and horizontal planes a substantial distance above the top of said truck
20 25

64. In a mining apparatus, a portable base, a single rigid arm pivotally mounted on said base to swing in a vertical direction in longitudinal planes relative thereto, a cutter support pivotally mounted on the outer extremity of said arm to swing relative thereto about an axis parallel with the arm axis, a kerf cutter pivotally mounted on said cutter support to swing relative thereto, and a motor on said base and relative to which said arm is swingable for swinging said arm relative to said base, for swinging said cutter support relative to said arm and for actuating said kerf cutter.
30 35

65. In a mining apparatus, a portable base, an arm pivotally mounted on said base to swing in a vertical direction in longitudinal planes relative thereto, a cutter support pivotally mounted on the outer extremity of said arm to swing relative thereto about an axis parallel with the arm pivot axis, a kerf cutter pivotally mounted on said cutter support to swing relative thereto, and motor operated means for independently swinging said arm and cutter support about their respective pivots.
40 45

66. In a mining apparatus, a portable base, an arm pivotally mounted on said base to swing in a vertical direction relative thereto, a cutter support pivotally mounted on the outer extremity of said arm to swing relative thereto about an axis parallel with the arm pivot axis, a kerf cutter pivotally mounted on said cutter support to swing relative thereto, motor operated devices for actuating said kerf cutter including a motor driven shaft extending lengthwise of and journaled on said arm, an element coaxial with the cutter support pivot and driven by said shaft and a shaft journaled on said cutter support and driven by said coaxial element and operatively connected to the kerf cutter, and devices driven by said first mentioned shaft for swinging said kerf cutter about its pivot.
50 55 60 65

67. In a mining apparatus, a portable base, an arm pivotally mounted on said base to swing in a vertical direction relative thereto, a cutter support pivotally mounted on the outer extremity of said arm to swing relative thereto about an axis parallel with the arm pivot axis, a kerf cutter pivotally mounted on said cutter support to swing relative thereto, motor operated devices for actuating said kerf cutter including a motor
70 75

driven shaft extending lengthwise of and journaled on said arm, an element coaxial with the cutter support pivot and driven by said shaft and a shaft journaled on said cutter support and 5 driven by said coaxial element and operatively connected to the kerf cutter, and devices driven by said coaxial element for swinging said kerf cutter about its pivot.

68. In a mining apparatus, a portable base, 10 an arm pivotally mounted on said base to swing in a vertical direction relative thereto, a cutter support pivotally mounted on the outer extremity of said arm to swing relative thereto about an axis parallel to the swinging axis of said arm, 15 a kerf cutter pivotally mounted on said cutter support to swing relative thereto, motor operated devices for actuating said kerf cutter including a motor driven shaft journaled on said arm, and motor operated devices for swinging 20

said kerf cutter relative to said cutter support including a worm gear coaxial with the cutter pivot and connectible to the cutter, and a worm meshing with said worm gear and driven by said shaft.

25 69. In a mining apparatus, a portable base, an arm pivotally mounted on said base to swing in a vertical direction relative thereto, a cutter support pivotally mounted on the outer extremity of said arm to swing relative thereto about an 30 axis parallel with the axis of swinging movement of said arm, a kerf cutter pivotally mounted on said cutter support to swing relative thereto, a motor on said base, devices actuated by said motor for actuating the kerf cutter including a shaft 35 driven by said motor and journaled on said base, a transmission element coaxial with the arm pivot and driven by said shaft, a shaft extending lengthwise of and journaled on said arm and driven by said coaxial element, an element coaxial with the cutter support pivot and driven by said last mentioned shaft, a shaft journaled on the cutter support and driven by said last 40

45 said shaft journaled on said arm for swinging said arm about its pivot, and devices driven by said shaft journaled on said arm for swinging said kerf cutter about its pivot relative to said cutter support.

70 70. In a mining apparatus, a portable base, an arm pivotally mounted on said base to swing in a vertical direction relative thereto, a cutter support pivotally mounted on the outer extremity of said arm to swing relative thereto about an axis parallel with the axis of swinging movement of said arm, a kerf cutter pivotally mounted on said cutter support to swing relative thereto, a motor 50 on said base, devices actuated by said motor for actuating the kerf cutter including a shaft driven by said motor and journaled on said base, a transmission element coaxial with the arm pivot and driven by said shaft, a shaft extending lengthwise 55 of and journaled on said arm and driven by said coaxial element, an element coaxial with the cutter support pivot and driven by said last mentioned shaft, a shaft journaled on the cutter support and driven by said last mentioned coaxial 60 element and operatively connected to the kerf cutter, devices driven by said shaft journaled on said arm for swinging said cutter support about its pivot relative to said arm, and devices driven by said shaft journaled on said arm for 65 swinging said kerf cutter about its pivot relative to said cutter support.

71. In a mining apparatus, a portable base, an arm pivotally mounted on said base to swing in a vertical direction relative thereto, a cutter support pivotally mounted on the outer extremity of said arm to swing relative thereto about an 70 axis parallel with the axis of swinging movement

of said arm, a kerf cutter pivotally mounted on said cutter support to swing relative thereto, a motor on said base, devices actuated by said motor for actuating the kerf cutter including a shaft driven by said motor and journaled on said base, a transmission element coaxial with the arm pivot and driven by said shaft, a shaft extending lengthwise of and journaled on said arm and driven by said coaxial element, an element coaxial with the cutter support pivot and driven by said last mentioned shaft, a shaft journaled on the cutter support and driven by said last mentioned coaxial element and operatively connected to the kerf cutter, and devices driven by said shaft journaled on said arm for swinging said cutter support and said arm about their respective pivots.

72. In a mining apparatus, a portable base, an arm pivotally mounted on said base to swing in a vertical direction relative thereto, a cutter support pivotally mounted on the outer extremity of said arm to swing relative thereto about an axis parallel with the axis of swinging movement of said arm, a kerf cutter pivotally mounted on said cutter support to swing relative thereto, a motor on said base, devices actuated by said motor for actuating the kerf cutter including a shaft driven by said motor and journaled on said base, a transmission element coaxial with the arm pivot and driven by said shaft, a shaft extending lengthwise of and journaled on said arm and driven by said coaxial element, an element coaxial with the cutter support pivot and driven by said last mentioned shaft, a shaft journaled on the cutter support and driven by said last 35 mentioned coaxial element and operatively connected to the kerf cutter, devices driven by said shaft journaled on said arm for swinging said arm about its pivot, and devices driven by said shaft journaled on said arm for swinging said kerf cutter about its pivot relative to said cutter support.

73. In a mining apparatus, a portable base, an arm pivotally mounted on said base to swing in a vertical direction relative thereto, a cutter support pivotally mounted on the outer extremity of said arm to swing relative thereto about an axis parallel with the axis of swinging movement of said arm, a kerf cutter pivotally mounted on said cutter support to swing relative thereto, a motor 50 on said base, devices actuated by said motor for actuating the kerf cutter including a shaft driven by said motor and journaled on said base, a transmission element coaxial with the arm pivot and driven by said shaft, a shaft extending lengthwise 55 of and journaled on said arm and driven by said coaxial element, an element coaxial with the cutter support pivot and driven by said last mentioned shaft, a shaft journaled on the cutter support and driven by said last mentioned coaxial 60 element and operatively connected to the kerf cutter, devices driven by said shaft journaled on said arm for swinging said cutter support about its pivot relative to said arm, and devices driven by said shaft journaled on said arm for 65 swinging said kerf cutter about its pivot relative to said cutter support.

74. In a mining apparatus, a portable base, a kerf cutter swingable relative to said base to cut a vertical kerf, and adjustable supporting means 70 on said base for supporting said kerf cutter and adjustable to move said kerf cutter into parallel vertical cutting positions between the sides of said base and including a plurality of relatively adjustable supports, one mounted on the other 75

and rotatable relative to the base about parallel vertical axes and motor operated devices for independently rotating said supports about their respective axes, either support swingable relative to the other while the latter remains stationary as regards swinging movement about its own axis and said support mounted on the other support being movable upon rotation of the other support relative to the base bodily relative to the base to 10 positions from one side of the base to the other.

75. In a mining apparatus, a portable base, an arm pivotally mounted at its rear end on said base to swing in a vertical direction relative thereto about a horizontal axis extending transversely of said base, a cutter support pivotally mounted on the forward end of said arm to swing relative thereto about an axis parallel with the arm pivot axis, a horizontal kerf cutter pivotally mounted on said cutter support to swing relative thereto, and means for swinging said arm relative to said base and said cutter support relative to said arm to move said kerf cutter into parallel horizontal planes including horizontal planes above and below said base while the kerf cutter at all times remains in a horizontal cutting position, said cutter support being swingable, through a relatively wide range about its pivot relative to said arm while the latter remains stationary, into cutting positions at substantial angles at opposite sides of a horizontal plane including the support axis.

76. In a mining apparatus, a portable base, an arm pivotally mounted at its rear end on said base to swing in a vertical direction relative thereto about a horizontal axis extending transversely of said base, a cutter support pivotally mounted on the front end of said arm to swing relative thereto about an axis parallel with the arm pivot axis, a horizontal kerf cutter pivotally mounted on said cutter support to swing relative thereto, and means for swinging said arm relative to said base and said cutter support relative to said arm to move said kerf cutter into parallel horizontal planes including horizontal planes adjacent the mine floor and horizontal planes a substantial distance above the top of said base while the kerf cutter at all times remains in a horizontal cutting position, said cutter support being swingable, through a relatively wide range about its pivot relative to said arm while the latter remains stationary, into cutting positions at substantial angles at opposite sides of a horizontal plane including the support axis.

77. In a mining apparatus, a wheeled truck adapted to run along a mine trackway, an arm pivotally mounted on the forward end of said truck to swing in a vertical direction relative thereto about a horizontal axis extending transversely of the apparatus in advance of the front truck wheel axes, a cutter support pivotally mounted on the outer extremity of said arm, a horizontal kerf cutter carried by said cutter support, and motor operated means for swinging said arm and cutter support about their respective axes to move the kerf cutter into parallel horizontal planes including horizontal planes above and below said truck, said cutter support being swingable by said motor operated means through a relatively wide range relative to said arm while the latter remains stationary.

78. In a mining apparatus, a wheeled truck adapted to run along a mine trackway, an arm pivotally mounted on the forward end of said truck to swing in a vertical direction relative thereto about a horizontal axis extending trans-

versely of the apparatus in advance of the front truck wheel axes, a cutter support pivotally mounted on the outer extremity of said arm, a horizontal kerf cutter carried by said cutter support, and motor operated means for swinging said arm and cutter support about their respective axes to move the kerf cutter into parallel horizontal planes including horizontal planes adjacent the mine floor and horizontal planes a substantial distance above the top of said truck, said cutter support being swingable by said motor operated means through a relatively wide range relative to said arm while the latter remains stationary.

79. In a mining apparatus, a portable base, an arm pivotally mounted on said base to swing in a vertical direction in longitudinal planes relative thereto, a cutter support pivotally mounted on the outer extremity of said arm to swing relative thereto about an axis parallel with the arm pivot axis, a kerf cutter pivotally mounted on said cutter support to swing relative thereto, and a motor on said base and relative to which said arm is swingable for swinging said arm relative to said base, for swinging said cutter support relative to said arm and for actuating said kerf cutter, said cutter support being swingable by said motor through a relatively wide range relative to said arm while the latter remains stationary.

80. In a mining apparatus, a portable base, an arm pivotally mounted on said base to swing in a vertical direction relative thereto about a horizontal axis extending transversely of said base, a cutter support pivotally mounted on the outer extremity of said arm to swing relative thereto about an axis parallel with the arm pivot axis, a horizontal kerf cutter pivotally mounted on said cutter support to swing relative thereto, and means for swinging said arm through at least 45° about its axis relative to said base and said cutter support relative to said arm to move said kerf cutter into parallel horizontal planes including horizontal planes above and below said base while the kerf cutter at all times remains in a horizontal cutting position.

81. In a mining apparatus, a portable base, an arm pivotally mounted on said base to swing in a vertical direction relative thereto about a horizontal axis extending transversely of said base, a cutter support pivotally mounted on the outer extremity of said arm to swing relative thereto about an axis parallel with the arm pivot axis, a horizontal kerf cutter pivotally mounted on said cutter support to swing relative thereto, and means for swinging said arm through substantially 90° about its axis relative to said base and said cutter support relative to said arm to move said kerf cutter into parallel horizontal planes including horizontal planes above and below said base while the kerf cutter at all times remains in a horizontal cutting position.

82. In a mining apparatus, a portable base, an arm pivotally mounted on said base to swing in a vertical direction relative thereto about a horizontal axis extending transversely of said base, a cutter support pivotally mounted on the outer extremity of said arm to swing relative thereto about an axis parallel with the arm pivot axis, a horizontal kerf cutter pivotally mounted on said cutter support to swing relative thereto, and means for swinging said arm through at least 45° about its axis relative to said base and said cutter support relative to said arm to move said kerf cutter into parallel horizontal planes in-

- cluding horizontal planes above and below said base while the kerf cutter at all times remains in a horizontal cutting position, said cutter support being swingable through at least 90° about 5 its axis relative to said arm.
83. In a mining apparatus, a portable base, an arm pivotally mounted on said base to swing in a vertical direction relative thereto about a horizontal axis extending transversely of said 10 base, a cutter support pivotally mounted on the outer extremity of said arm to swing relative thereto about an axis parallel with the arm pivot axis, a horizontal kerf cutter pivotally mounted on said cutter support to swing relative thereto, and means for swinging said arm through substantially 15 90° about its axis relative to said base and said cutter support relative to said arm to move said kerf cutter into parallel horizontal planes including horizontal planes above and below said base while the kerf cutter at all times remains in a horizontal cutting position, said cutter support being swingable through substantially 20 90° about its axis relative to said arm.
84. In a mining apparatus, a portable base, an arm pivotally mounted on said base to swing in a vertical direction relative thereto about a horizontal axis extending transversely of said 25 base, a cutter support pivotally mounted on the outer extremity of said arm to swing relative thereto about an axis parallel with the arm pivot axis, a horizontal kerf cutter pivotally mounted on said cutter support to swing relative thereto, and means for swinging said arm through at least 30 45° about its axis relative to said base and said cutter support relative to said arm to move said kerf cutter into parallel horizontal planes including horizontal planes adjacent the mine floor and horizontal planes a substantial distance above the top of said base while the kerf cutter at all 35 times remains in a horizontal cutting position.
85. In a mining apparatus, a portable base, an arm pivotally mounted on said base to swing in a vertical direction relative thereto about a horizontal axis extending transversely of said base, a cutter support pivotally mounted on the outer 40 extremity of said arm to swing relative thereto about an axis parallel with the arm pivot axis, a horizontal kerf cutter pivotally mounted on said cutter support to swing relative thereto, and means for swinging said arm through substantially 45 90° about its axis relative to said base and said cutter support relative to said arm to move said kerf cutter into parallel horizontal planes including horizontal planes adjacent the mine floor and horizontal planes a substantial distance above the top of said base while the kerf cutter at all 50 times remains in a horizontal cutting position.
86. In a mining apparatus, a portable base, an arm pivotally mounted on said base to swing in a vertical direction relative thereto about a horizontal axis extending transversely of said base, a cutter support pivotally mounted on the outer extremity of said arm to swing relative thereto about an axis parallel with the arm pivot axis, a horizontal kerf cutter pivotally mounted on said cutter support to swing relative thereto, and means for swinging said arm through at least 55 45° about its axis relative to said base and said cutter support relative to said arm to move said kerf cutter into parallel horizontal planes including horizontal planes adjacent the mine floor and horizontal planes a substantial distance above the top of said base while the kerf cutter at all 60 times remains in a horizontal cutting position.
87. In a mining apparatus, a portable base, an arm pivotally mounted on said base to swing in a vertical direction relative thereto about a horizontal axis extending transversely of said base, a cutter support pivotally mounted on the outer extremity of said arm to swing relative thereto about an axis parallel with the arm pivot axis, a horizontal kerf cutter pivotally mounted on said cutter support to swing relative thereto, and means for swinging said arm through substantially 65 90° about its axis relative to said base and said cutter support relative to said arm to move said kerf cutter into parallel horizontal planes including horizontal planes adjacent the mine floor and horizontal planes a substantial distance above the top of said base while the kerf cutter at all 70 times remains in a horizontal cutting position.
88. In a coal mining machine, a chassis, a rotatable head on one end thereof having a projecting supporting bracket with a segmental gear thereon, a link pivoted on said bracket, gearing on said link engageable with said segmental gearing, a cutter support, mounted on the free link end and pivoted thereon, said cutter support having a similar segmental gear fixed thereon for changing the angular position of the cutter support with respect to said link.
89. In a coal mining machine, in combination with a chassis and a cutter bar having cutting means thereon, means on the chassis for operating the cutting means, and a connecting means between the chassis and the cutter bar, said connecting means comprising a link having a plurality of worms connected with a suitable part of the chassis for elevating the cutter bar, a plurality of worms connected with a suitable part of the cutter bar to elevate the cutter bar, and a common drive means for said worms.
90. In a mining apparatus, a portable base, an arm structure comprising but a single rigid arm pivotally mounted on said base to swing in a vertical direction relative thereto about a horizontal axis extending transversely of said base, said arm extending lengthwise of said base, a cutter support pivotally mounted on the outer extremity of said arm structure to swing through a relatively wide range relative thereto about an axis parallel with the arm structure axis while said arm remains stationary as regards vertical swinging movement, and a kerf cutter pivotally mounted on said cutter support to swing relative thereto, said support being swingable relative to said arm to move the kerf cutter into cutting positions at substantial angles at opposite sides of a plane including the support axis.
91. In a mining apparatus, a portable base, an arm pivotally mounted on said base to swing in a vertical direction relative thereto about a transverse axis and extending lengthwise of said base, a cutter support pivotally mounted on the outer extremity of said arm to swing through a relatively wide range relative thereto about an axis parallel with the arm axis, a kerf cutter pivotally mounted on said cutter support to swing relative thereto, said cutter support being swingable relative to said arm to move the kerf cutter into cutting positions at substantial angles at opposite sides of a plane including the support axis, and motor driven means for actuating said kerf cutter.

including a shaft journaled on said arm, and means driven by said shaft for swinging said cutter support about its pivot.

92. In a coal mining machine, a chassis, a rotatable head mounted theron for supporting a coal cutter, a coal cutter, a support therefor pivotable on a vertical axis, a link pivotally connecting said support for the cutter to said rotatable head, gearing on said cutter support and rotatable head respectively, gearing on said link engaging therewith, and means for alternately driving said gearing to change the elevation and angular position of said cutter while said rotatable head remains stationary.
93. In a coal mining machine, a chassis, a rotatable head mounted thereon for supporting a coal cutter, a coal cutter, a support therefor pivoted on a vertical axis, a link pivotally connecting said support for the cutter to said rotatable head, gearing on said cutter support and rotatable head respectively, gearing on said link engaging therewith, means for alternately driving said gearing to change the elevation and angular position of said cutter while said rotatable head remains stationary, and means on said cutter support for rotating said cutter about its vertical axis.

94. In a coal mining machine, in combination with a chassis and a cutter bar, a support for supporting the cutter bar, means for connecting the support to the chassis, and means on the chassis for operating the cutter bar, said first means comprising a link structure having thereon means cooperating with the chassis for elevating the support and the cutter bar by swinging in planes extending longitudinally of the machine between the sides thereof.

95. In a coal mining machine, in combination with a chassis and a cutter bar, a support for supporting the cutter bar, means for connecting the support to the chassis, and means on the chassis for operating the cutter bar, said first means comprising a link structure having thereon means cooperating with the chassis for elevating the support and the cutter bar by swinging in planes extending longitudinally of the machine between the sides thereof, and means for tilting the cutter bar.

96. In a coal mining machine, in combination with a chassis and a cutter bar, a support for supporting the cutter bar, means for connecting the support to the chassis, cutter means on the cutter bar and means on the chassis for operating said cutting means, said connecting means comprising means cooperating with the chassis for swingingly elevating the support and the cutter bar, means cooperating with the cutter bar to further swingingly elevate the cutter bar by continued movement in the same planes, and means to operate both the said last named means independently or conjunctively.

97. In a coal mining machine, in combination with a chassis and a cutter bar having cutting means thereon, means on the chassis for operating the cutting means, and a connecting means between the chassis and the cutter bar, said connecting means comprising a link having a plurality of worms connected with a suitable part of the chassis for elevating the cutter bar, a plurality of worms connected with a suitable part of the cutter bar to elevate the cutter bar, a common drive means for said worms, and means for selectively connecting said drive to said worms.

98. In a coal mining machine, in combination with a chassis and a cutter bar, means for con-

necting the chassis to the cutter bar comprising a link structure having thereon a plurality of worms operatively connected to some part of the chassis, a second pair of worms operatively connected to some part of the cutter bar, a motor, and a clutch connection between each pair of worms and the motor.

99. In a coal mining machine, in combination with a chassis having thereon a rotating head and a cutter support having thereon a cutter bar, means connecting the rotating head to the cutter support comprising a link structure pivotally connected to each and having thereon a gear mechanism operatively connected to the rotating head for elevating the link structure, a second gear mechanism operatively connected to the cutter support for elevating the cutter bar, power means located on said connecting means, and means for connecting said power means to either of said gear mechanism.

100. In a coal mining machine, in combination with a chassis and a cutter bar, a connection between said chassis and said cutter bar comprising a link structure having a pivotal connection at each end thereof and having thereon means cooperating with the chassis for elevating the cutter bar, a second means thereon cooperating with the cutter bar for elevating the cutter bar, a motor for operating both of said means, and means for controlling the operation of said motor to cause the operation of said first-named means or to cut out the motor and stop the operation thereof.

101. In a coal mining machine, a chassis, means for transporting the chassis, a rotatable supporting head on the chassis rotatable on a horizontal axis, means on the chassis for rotating the head, a rotatable support supported by the supporting head and rotatable relative thereto, a cutter carried by the rotatable support and pivotable relative thereto, means on the chassis for driving the cutter irrespective of the rotative position of the supporting head, and power means on the rotatable support supported adjacent the cutter to rotate the cutter about an axis on said rotatable support relative to the latter.

102. In combination, a chassis, a longitudinally extending rotatable head thereon, a rotatable support carried by said rotatable head and rotatable relative to the latter, a cutter mounted on said rotatable support, means to rotate said cutter about a vertical axis to different positions with respect to the rotatable support and to drive said cutter irrespective of its position, power means on the rotatable support supported adjacent the cutter to adjust the angular position of the cutter with respect to the rotatable head, and means to adjust the elevation of the cutter.

103. In a mining apparatus, a wheeled truck, kerf cutting mechanism including a cutter bar support carrying a cutter bar swingably mounted with respect thereto and an adjustable supporting structure intervening said truck and cutting mechanism including an arm pivotally connected to said truck and on which said cutter bar support is pivotally mounted, said arm and support being swingable about axes arranged at angles to the longitudinal axis of the apparatus to move the cutter bar into parallel or other planes, motor-operated devices for swinging said arm about its pivot relative to said truck, and separate motor-operated devices for swinging said bar support about its pivot relative to said arm.

104. In a mining apparatus, a wheeled truck, an arm pivotally mounted on the forward end of said truck, kerf cutting mechanism adjustably supported at the forward end of said arm and including a forwardly projecting kerf cutter, and devices carried by said arm for swinging said arm about its pivot and adjusting said kerf cutting mechanism on said arm to adjust said cutter bar into different planes while said cutter bar is maintained parallel to any desired plane. 5
105. In a mining apparatus, a wheeled truck, an arm pivotally mounted on the forward end of said truck, kerf cutting mechanism adjustably supported at the forward end of said arm and including a forwardly projecting kerf cutter, and devices carried by said arm for swinging said arm about its pivot and adjusting said kerf cutting mechanism on said arm to adjust said cutter bar into different planes while said cutter bar is maintained parallel to any desired plane. 10

CHARLES F. OSGOOD.
